UNITED STATES PATENT OFFICE.

ALBERT H. STEBBINS, OF LITTLE ROCK, ARKANSAS.

ORE-CONCENTRATOR.

SPECIFICATION forming part of Letters Patent No. 696,606, dated April 1, 1902.

Application filed October 29, 1900. Serial No. 34,748. (No model.)

To all whom it may concern:

Be it known that I, ALBERT H. STEBBINS, a citizen of the United States, residing at Little Rock, in the county of Pulaski and State 5 of Arkansas, have invented certain new and useful Improvements in Ore-Concentrators, of which the following is a specification.

The invention to be hereinafter described relates to ore-concentrators for effecting a 10 separation of the valuable particles of ore from their adhering impurities, and more particularly to that type of such machine wherein the ore, preferably in a finely-divided condition, is subjected to the action of fluid-currents, which serve to eliminate the light value- 15 less particles and carry the same away from the heavy or valuable particles.

It is a well-known fact that the particles of comminuted or finely-ground ores vary in size 20 and shape and often in specific gravities, and to facilitate the subsequent treatment of such particles it is desirable that those of similar size and like specific gravities shall be collected in a group and separated from those of 25 different size and unlike specific gravities and that the adhering or intermixed impurities be separated from all the groups thus segregated. With these and other general objects in view I have invented a form of ore-concen- 30 trator having an incasement of gradually-increasing size from one end to the other and in which the divided or finely-ground ore is subjected to the action of air or other fluid caused to circulate in substantially circular 35 or spiral currents of gradually-decreasing strength or carrying capacity from the smaller to the larger end of the incasement, so that while the fluid-currents near the smaller end of the incasement will carry in their circular 40 or spiral course nearly all the material fed to the machine the same fluid-currents at a point more remote from said smaller end will be so far reduced in strength by reason of the increased size of the incasement that many of 45 the heavier particles will no longer be sustained and will fall into a receptacle provided for the purpose, the lighter values and impurities still continuing to be held in suspension and circulated by the reduced current 50 until the gradual and successive weakening of the fluid-currents permits the lighter and then the lightest values to settle or fall, while

the impurities are carried out of the machine. By this operation not only are the valuable particles or portions of ore separated from the 55 accompanying sand, dirt, or other impurities, but the valuable particles are themselves separated into groups according to their size or relative specific gravities, and thus collected for further treatment. 60

The machine which forms the subject of my present invention is primarily designed for the treatment of ground or finely-divided ores or like materials, but may be applicable for treatment of materials in other conditions, 65 and while I describe the operation of the device by the use of air-blasts for effecting the separation outlined it is obvious that any fluid may be used with advantage, according to the character of the material being treated. 70

My invention as above generally indicated consists of the parts and combinations, as will be hereinafter more particularly described, and definitely pointed out in the claims.

In the drawings, Figure 1 is a plan view of 75 a concentrator embodying my invention, part of the wall being broken away at one end to disclose the construction within. Fig. 2 is a side elevation of a concentrator embodying my invention. Fig. 3 is a cross-section on 80 line $x-x$, Fig. 2. Fig. 4 is a detail view of the distributing pipe and chute. Fig. 5 is a cross-section of a modification.

The concentrator in the present embodiment of my invention comprises an incasement 85 A, preferably of funnel shape—that is, of gradual increasing cross-sectional area from one end to the other, the smaller end a being closed, while the larger end a' is open. Extending lengthwise of the incasement A is 90 a distributing-pipe B, the length of which may be more or less, as desired; but, as shown, the distributing-pipe extends continuously nearly the entire length of the incasement A and is connected to any suitable fluid-supplying means, not necessary to show, by the connection B', preferably, though not necessarily, located to convey the fluid blast into the distributing-pipe B, near one end thereof. The distributing-pipe B is connected to the incasement A by the introduction-chute C, arranged, preferably, tangential to the incasement, which is provided with an opening C' to receive the end walls of the chute. It will 100

be noted that the cross-section of the incasement is substantially circular and that the wall thereof at the point where the chute C connects with the incasement A is carried out of its circular course, as shown in Fig. 3, thereby forming at the bottom of the incasement a supporting-incline a^2 , onto which the particles of ore may fall and the blast of air from the chute C be directed.

- 10 Preferably some distance above the supporting incline a^2 the incasement is provided with a slit a^3 , which may extend substantially the length of the incasement and forms the outlet or discharge opening for the concentrates. Extending downward from the slit, on either side thereof, is a flange a^4 , projecting into the concentrate-boxes D, which may be closed at or near their ends by doors d , free to swing outward, as shown, to permit the 15 concentrates to be discharged, but adapted to close and prevent the ingress of air should the moving air-currents in the incasement create a suction or partial vacuum in the concentrate-box. The concentrate-boxes D extend throughout the length of the outlet or 20 discharge slit a^3 , and the partitions d' between the boxes serve as braces to support and strengthen the wall of the incasement on opposite sides of the slit.
- 25 30 The ground or divided ore is introduced into the incasement A, at the small end thereof, by means of a hopper E or other desired or usual means and is at once caught by the incoming blast of air which issues from the 35 introduction-chute C and passes into the incasement substantially tangential therewith, striking first and with the greatest energy the supporting-incline a^2 , on which much of the material being treated will fall. Under the 40 lifting force of the incoming blast of air the mass of material is started in a circular path around the interior of the funnel-shaped incasement, some of the heavier particles being forced up the incline over the edge of the discharge-opening a^3 , while others are carried 45 past said opening and falling back under the influence of gravity pass into said opening a^3 , the lighter particles and impurities being given a gyratory motion while suspended by 50 the air-currents. As the gyratory motion of the air-currents carries the material to the larger cross-sectional areas of the incasement those particles which were before held in suspension by the force of the blast are now permitted 55 to settle under the decreased action of the blast and eventually find their way into the discharge-opening a^3 , as above indicated. It will be noted that the distributing-chute C delivers the air or fluid blast into the lower 60 portion of the incasement and directly over and upon the supporting-incline a^2 , and such blast as it enters the incasement being strongest at this point will lift and pick up any settling that may lodge upon the supporting-incline 65 to eventually carry them up the incline into the discharge-opening a^3 . It will be noted that I have provided flanges project-

ing downward from the discharge-opening a^3 into the concentrate-boxes, the purpose of this being to overcome to some extent the 70 fluctuating movements that are liable to occur through the discharge-opening a^3 under the varying pressures exerted by the gyratory air-currents in the incasement, and to further prevent this back-and-forth movement of air-currents through the discharge-opening a^3 I 75 may provide the concentrate-boxes with a door, as d , which upon the creation of a partial vacuum in the box would be closed, as will be evident.

80 Preferably located at intervals along the distributing-chute C are partitions e , which serve the double purpose of acting as braces to hold the introduction-chute in shape and as wings to guide the air into the funnel or 85 incasement at a direct right angle or such other angle as may be desired to get the best circular motion. These partitions may be located at any desired intervals in the introduction-chute, depending largely upon the 90 character of material to be treated and the character of blast introduced or the character of motion desired to be given to the material within the funnel or incasement.

95 Preferably within the funnel at any desired intervals I place spiral flanges or guide-pieces f , which may extend more or less around the interior of the funnel and project inward from the wall thereof a suitable distance to act as a guide giving to the air-currents their 100 circular movement. In the form shown in Fig. 3 the flanges f are crescent-shaped and extend only part way around the funnel on the side thereof opposite the distributing-chute; but it will be understood that these 105 flanges may be longer or shorter, as desired, their purpose being to assist in holding the air-currents from too rapid longitudinal movement of the funnel and to guide them into circular paths. These flanges or wings 110 act also as braces for the funnel, especially when the latter is made of light metal, as may be found sometimes desirable.

115 In the modified construction shown by Fig. 5 the incasement is provided with two discharge-openings k k' , and the number of said openings, it will be obvious, may be varied as desired; but in any event said discharge-openings should lead to separate concentrate-boxes K K' , into which project the flanges on 120 opposite sides of the openings. It will be obvious that when two or more discharge-openings are employed the concentrates in passing up the supporting-incline will be more liable to pass through one of the discharge-openings, so as to more readily separate the concentrates from their lighter impurities.

125 The disposition of the distributing-pipe and its connection with the source of supply and distributing-chute should be such that the fluid or air exerts its greatest force in the small end of the funnel or incasement, and from there the exerted force should decrease 130

proportionately as the funnel is traversed to its exit end.

The partitions d' between the concentrate-boxes serve to brace the walls of the funnel-shaped incasement where the same is provided with the discharge-opening a^3 .

In the same cases it may be desirable to contract the outlet at the large end of the funnel in order to increase the effectiveness of the air-currents in carrying the light impurities out of the machine, and as one means of accomplishing this result I may employ a detachable cone or other shaped flange or funnel m , having a rim m' to fit over the end of the casing, the smaller end of the flange or funnel m preferably, though not necessarily, projecting into the interior of the concentrator, as shown by dotted lines in Fig. 1.

Having described my invention, what I claim, and desire to secure by Letters Patent, is—

1. In an ore-concentrator, the combination of a funnel-shaped incasement of gradually-increasing cross-sectional area from one end to the other, said incasement being closed at its smaller end, a feed-hopper leading into the funnel-shaped incasement at its smaller end, a fluid-distributing chute tangentially arranged with reference to said incasement and leading into the same, an outlet for the concentrates, located in the wall of the incasement above the lowest portion thereof, and a series of concentrate-boxes in communication with said outlet, whereby as material fed into the incasement at its smaller end is given a spiral or gyratory motion within the incasement and moved toward the larger end thereof, the concentrates or heavier particles are subjected to decreased fluid-currents and pass through the outlet into the concentrate-boxes according to their specific gravity.

2. In an ore-concentrator, the combination of an incasement of gradually-increasing cross-sectional area from one end to the other, said incasement being closed at its smaller end, an air-distributing chute tangentially arranged with reference to said incasement extending substantially the length of said incasement and leading into the same, an outlet for the concentrate, and a series of concentrate-boxes in communication with said outlet.

3. In an ore-concentrator, the combination of a funnel-shaped incasement of gradually-increasing cross-sectional area from one end to the other, said incasement being closed at its smaller end, means to feed material to said incasement, a distributing-pipe, a fluid-distributing chute connected to said pipe and extending substantially the length of said incasement and being tangentially connected thereto to produce within said incasement circular fluid-currents, and an outlet for the concentrates.

4. In an ore-concentrator, the combination of a funnel-shaped incasement of gradually-

increasing cross-sectional area from one end to the other, said incasement being closed at its smaller end, means to feed material into said incasement, a distributing-pipe and a fluid-distributing chute extending substantially the length of said incasement, and the chute being arranged tangential thereto, a discharge-outlet for the concentrates extending substantially the length of the incasement and a series of concentrate-boxes in communication with said outlet.

5. In an ore-concentrator, the combination of a funnel-shaped incasement of gradually-increasing cross-sectional area from one end to the other, said incasement being closed at its smaller end, means to feed material into said incasement, a distributing-pipe and a fluid-distributing chute extending substantially the length of said incasement, and the chute being arranged tangential thereto, a discharge-outlet for the concentrates arranged in the wall of the incasement above the bottom thereof and opposite the distributing-chute.

6. In an ore-concentrator, the combination of a funnel-shaped incasement of gradually-increasing cross-sectional area from one end to the other and having a supporting-incline, means for feeding material into said incasement near the smaller end thereof, a distributing-pipe, a distributing-chute connected thereto and arranged tangentially to the incasement to direct a blast of air directly onto and over the supporting-incline thereof, a discharge-outlet arranged in the wall of the incasement above the supporting-incline and on the side thereof opposite the distributing-chute.

7. In an ore-concentrator, the combination of a funnel-shaped incasement of gradually-increasing cross-sectional area from one end to the other and having a supporting-incline, a distributing-pipe and a distributing-chute extending substantially the length of said incasement, the said chute being connected tangentially thereto to direct a blast of air onto the said supporting-incline, a discharge-outlet in the wall of the incasement opposite the distributing-chute and a series of concentrate-boxes in communication with the said outlet.

8. In an ore-concentrator, the combination of a funnel-shaped incasement of gradually-increasing cross-sectional area from one end to the other and having a supporting-incline, a distributing-pipe and a distributing-chute extending substantially the length of said incasement, the said chute being connected tangentially thereto to direct a blast of air onto the said supporting-incline, a discharge-outlet in the wall of the incasement opposite the distributing-chute, and a series of concentrate-boxes, said outlet having flanges projecting into the concentrate-boxes.

9. In an ore-concentrator, the combination of a funnel-shaped incasement of gradually-increasing cross-sectional area from one end to

- the other and having a supporting-incline, a distributing-pipe and a distributing-chute extending substantially the length of said incasement, the said chute being connected 5 tangentially thereto to direct a blast of air onto the said supporting-incline, a discharge-outlet in the wall of the incasement opposite the distributing-chute, and a series of concentrate-boxes having self-closing and normally closed doors, said outlet having flanges projecting into the concentrate-boxes.
10. In an ore-concentrator, the combination of a funnel-shaped incasement of gradually increasing cross-sectional area from one end to 15 the other and having a supporting-incline, a distributing-pipe and a distributing-chute extending substantially the length of the incasement, the said chute having partitions therein and connected tangentially to the incasement to direct a blast of air onto the said supporting-incline, a discharge-outlet in the side wall of the incasement opposite the distributing-chute and a series of concentrate-boxes in communication with said outlet.
- 20 11. In an ore-concentrator, the combination of a funnel-shaped incasement of gradually increasing cross-sectional area from one end to the other and having a supporting-incline, a distributing-pipe and a distributing-chute extending substantially the length of the incasement, the said chute having partitions

therein and connected tangentially to the incasement to direct a blast of air onto the said supporting-incline, a discharge-outlet in the side wall of the incasement opposite the distributing-chute, a series of flanges projecting inward from the wall of the funnel and a series of concentrate-boxes in communication with said outlet.

12. In an ore-concentrator, the combination 40 of an incasement of gradually increasing cross-sectional area from one end to the other and having a supporting-incline, means for feeding material into the same near the smaller end thereof, a fluid-distributing chute connected thereto and arranged tangentially to the incasement to direct a fluid-blast directly onto and over the supporting-incline, and a discharge-opening in the wall of the incasement opposite the tangential inlet and above 45 the supporting-incline so that material falling down the wall of the incasement after being projected above the discharge-opening by the incoming blast will pass through said discharge-opening.

55 In testimony whereof I have signed my name to this specification in the presence of two subscribing witnesses.

ALBERT H. STEBBINS.
